Shigley & Harvey

ATTORNEYS

UNITED STATES PATENT OFFICE.

GERALD J. MULLIGAN, OF COLUMBUS, OHIO.

CONTAINER.

Application filed December 8, 1921. Serial No. 520,964.

To all whom it may concern:

Be it known that I, GERALD J. MULLIGAN, a citizen of the United States of America, residing at Columbus, in the county of 5 Franklin and State of Ohio, have invented certain new and useful Improvements in Containers, of which the following is a specification.

My present invention relates generally to 10 containers for holding various articles and commodities and more particularly to a container having a self-closing cover, my object being the provision of a container whose cover under normal circumstances may be 15 shifted to permit of the desired access to the interior of the container and will upon release return by gravity to the normal closed position, and a further object is the provision of an arrangement of this character which will admit of the use of the container for the purpose of holding various 20 articles including those articles best supported in a bag or flexible receptacle normally disposed within the container and 25 bodily removable therefrom.

In the accompanying drawing which illustrates my present invention and forms a part of this specification,

Figure 1 is a side view with the cover 30 closed,

Figure 2 is a similar view with the cover open,

Figure 3 is an enlarged vertical section showing a slightly modified form,

Figure 4 is a partial horizontal section taken through Figure 3, and

Figures 5 and 6 are side views showing ornamental forms of covers.

Referring now to these figures the invention resides in a container which may be of the simple vertically cylindrical form indicated at 10 in Figures 1 and 2, having a closed base 11 and an upper open end, and provided in accordance with my invention 45 with an axial cover supporting stem 12 which projects above the upper open end for the support of an automatically closing cover 13. I prefer, and have shown this cover of conical form, its lower widest end 50 being substantially the same in diameter as the container 10 and its apex having a rounded socket 14 adapted to receive a ball-like enlargement 15 at the upper end of the stem 12 so that the cover is in effect

provided with a universally movable connection with the upper end of the supporting stem in order that it may swing laterally in all directions and thus permit of ready access to the interior of the container.

The stem 12 may as shown in Figures 1 and 2 rise from the base 11 of the container either with or without lateral braces 16 connecting the same with the side wall of the container as shown in Figure 2, while as indicated in Figure 3 the stem 12 extends 65 downwardly to a point but slightly beneath the upper edge of the container and may have a right angular lower portion 17 whose angular end is hinged or pivoted in the bracket 18 secured to the inner surface of 70 the wall of the container 10 so that the cover 13^a can swing as contemplated in the structure shown in Figures 1 and 2 and can also be bodily shifted along with the supporting stem to one side of the container in 75 the bracket 18 so as to permit of the introduction or removal of an inner flexible receptacle or the like 19 which may be normally supported upon hooks 20 within the container. In this latter form of construction as shown in Figures 3 and 4 the angular end of the lower arm 17 of the stem will have an angular extension 21 engaging the inner surface of the container to hold the stem 12 in its normal upright position 85 axially of the container.

As shown also in Figure 3 the upper rounded socket 14^a of the cover 13^a may have an upstanding handle 22 instead of relying merely upon the rounded socket itself as a handle and as indicated in Figures 5 and 6, ornamental pieces 23 and 24 in the form of representations of birds, or figures, may be secured upon the cover to 90 form a handle therefor.

It is obvious that the lid or cover as proposed by my invention permits of the use of the container for various purposes and in various sizes, it being possible to utilize the same in smaller sizes for various toilet 100 purposes, as powder containers, hair receivers and also as ash receivers and the like and that it can be used with equal facility in large sizes as ash cans and waste cans of various characters. It will also be appreciated that the lid or cover is free at all 105 times to swing open toward any side and to swing inwardly to closed position from

any point around the container and that gravity alone provides for its return movement when it is swung to the open position upon the upper end of the supporting stem.

5 I claim:

1. A container having an upper open end, a stem rising axially from the container above its said upper end, and a cover having a universally movable connection axially thereof upon the upper end of the said stem.
- 10 2. A container having an upper open end, a stem rising axially from the container and above said upper end thereof and provided with a ball-like enlargement at its upper end, and a conical cover having a rounded socket at its apex in which the enlargement of the stem is movably associated the ball and socket forming a universally movable connection on which the cover can 20 tilt laterally in all directions around the axis of the container.
- 15 3. A container having an upper open end, a stem rising axially from the container above its said upper end, and a cover having a universally movable connection axially 25 thereof upon the upper end of the said stem and also provided with means project-

ing above its axis and forming a handle therefor.

4. A container having an upper open end, 30 a stem rising axially from the container above its said upper end, and a cover having a universally movable connection axially thereof upon the upper end of the said stem, said stem having a lower angular portion 35 pivotally connected to the inner surface of the container adjacent to the said upper end of the latter.

5. A container having an upper open end and a bearing bracket secured to its inner 40 surface adjacent to its upper open end, a stem adapted to rise axially from the container above its open end, having a lower horizontal portion provided with an angular end movable in the bearing bracket of the 45 container, and a cover having a universally movable connection upon the upper end of said stem, said angular end of the stem having a depending extension to engage the inner surface of the container and normally 50 support the stem in upright position.

In testimony whereof I have affixed my signature.

GERALD J. MULLIGAN.
